Specification of Letters Patent.

Patented Feb. 5, 1918.

Application filed March 3, 1916. Serial No. 61,797.

To all whom it may concern:

Be it known that I, HERMAN C. WELTER, a citizen of the United States, residing at Rochester, in the county of Monroe and 5 State of New York, have invented a new and Improved Check-Writing Machine, of which the following is a specification.

My invention, while relating to printing machines of the check protecting class in 10 general, has more especial reference to those commonly known as check writers, the function of which is to print in words on checks, drafts, or other negotiable instruments, the exact amount for which they are written. 15 The type characters are usually carried by a member which is movable to readily bring a selected line thereof opposite a platen, whereupon one of such printing members is moved toward the other for the printing 20 operation, and as a safeguard against erasure for fraudulently "raising" the amount payable the type and platen are so conformed to either perforate the material of the instrument held between them or 25 break the fibers thereof throughout the printed surface.

One of the objects of this invention is to provide a check writing machine of the character described that is of simple and 30 strong construction, and both easily and quickly operable.

Another object is to inclose the operating mechanism in a casing designed to permit instruments in writing other than the ordinary check or draft, as invoices, stock certificates, etc., or documents on legal cap paper, to be placed in the machine and printed on any desired line thereof.

A further object is to provide a visible 40 writing machine, that is, one in which, when printing along a single line, each word or character is brought into view of the operator before operation is begun to print the succeeding word or character; and because of this visible feature it is possible to 45 feed the check manually, instead of automatically as is usually done, a variable distance in order to obtain equal spacing and by so doing to greatly reduce the number 50 of operating parts, the manually controlled feed being practically as fast as the automatic.

And a still further object is to provide a 55 means carried by and movable with the type support for stripping the material printed

on from the type after each printing operation, and, also, to provide a new and novel means for retaining the instrument, as a check, in proper alignment.

The accompanying drawings illustrating 60 a machine constructed in accordance with my invention are as follows:—

Figures 1 and 2 are opposite side elevations of the machine; Fig. 3, is a plan view of the base with part of the cover plate removed and with the rear portion of the top part of the case shown in section taken along the line $x-y$ of Fig. 2; Fig. 4, a front elevation of the machine; Fig. 5, a vertical sectional view taken along the line x^1-y^1 70 of Fig. 4; Fig. 6, a vertical sectional view taken along the line x^2-y^2 of Fig. 2; Fig. 7, a sectional detail showing the lever connections for raising and lowering the type wheel; Fig. 8, a portion of the type wheel 75 in end view and the means for locking the same against rotation; Fig. 9, a plan view of the type wheel locking means; Fig. 10, a side view of the stripper device with parts of the printing and feeding mechanism shown in dotted lines; Fig. 11, a perspective view of the stripper; Fig. 12, a detail showing the means employed for preventing a lateral movement of the feed rollers; Fig. 13, a plan view of the base of 80 the machine with a check thereon, and showing in section the means for gaging the distance the check is to be fed after each successive printing operation; and Fig. 14, a detail of construction to be explained. 85

Similar reference characters refer to similar parts throughout the several views.

The operating mechanism of the machine is mostly contained within a casing or frame consisting of two separable parts, a base and 95 a top section. The base comprises a rectangular main front portion 1, having side walls which are reinforced by both longitudinally and transversely extending ribs 2 and 3, respectively, and a rear extension 4; 100 while the top comprises a four walled upright member 5 having outwardly extending side flanges 6 by which it is supported upon the base extension 4 and, at its upper end, an arm or neck 7 extending forwardly at substantially 90° therefrom and which terminates in a depending head 8. The parts 4 and 5 of the base and top section, respectively, are secured together by dowel pins 9 and screws 10, as seen in Fig. 3.

The base portion 1 has secured thereon by screws 11 a cover plate 12 for supporting a check,—which term will hereinafter mean any instrument that may be printed by the 5 machine,—and in which plate suitable slot openings are formed to receive the tops of the feed rollers 13 and the platen 14, the latter member being adjustably supported, in a manner to be explained in a boss 15 10 forming an integral part of one of the reinforcing ribs 3 of the base.

In the side walls of the head 8 are vertically extending openings 16 forming guide-ways for side arms 17 of a yoke 18 on the 15 cross bar 19 of which are integrally formed a pair of centrally disposed upwardly extending ears 20. These ears are pivotally connected with one end of a lever 21, the other end thereof having pivotal connection 20 with the outer ends of arms 22 formed on a member 23 extending between the side walls of the head 8 and secured on a shaft 24 revolvably mounted in such side walls. This shaft extends outwardly beyond the right 25 hand wall, with respect to Figs. 4 and 6, and has secured thereon one end of the rearwardly extending operating lever 25 which is provided at its free end with a suitable handle 26. On the rod 27, forming the pivotal connection between the lever 21 and arms 22, there is a coiled spring 28 having its 30 central portion engaging under the lever 21 while its ends engage against the member 23, the action of such spring being to return the 35 levers 21 and 22 from the position in which they are seen in Fig. 7 to their normal and inoperative position in which they are seen in Fig. 5 when downward pressure is released from the operating lever 25. The 40 throw of the lever 25 is limited in its downward movement by the engagement of the arms 22 with a stop 29 comprising a rod extending between the side walls of the head 8.

The side arms of the yoke are slidably vertically in the guide-ways 16 formed in the side walls of the head 8 and the yoke is held against lateral movement by side plates 30 and 31 covering the guide-ways and secured by screws to the outer faces of such side 45 walls. The plate 30 is slotted to receive and permit a raising and lowering with the yoke, which is effected by levers 21 and 22 above described, of a horizontally extending shaft 32 revolvably mounted in the side arms 17 and 50 55 on which and between the arms there is secured by a pin 33 the type wheel 34. This shaft extends outwardly beyond the left hand side wall of the head, with respect to Figs. 4 and 6, and has a dial wheel 35 secured thereon by means of a pin 36, such wheel being provided with suitable means, as the knurled head 37, for readily turning the same to bring any one of the designating characters located on the periphery thereof 60 65 into registration with the pointer 38 project-

ing outwardly from and secured to the upper end of the side plate 30, as seen in Figs. 2 and 6.

The type wheel 34 carries on its periphery and, preferably, formed integrally therewith 70 a plurality of equally spaced type bars 39 extending parallel with the axis of rotation, and characters designating the several lines of type are formed on the periphery of the dial wheel 35, as above stated, so that a selected line of type is brought into printing position above the platen 14 by turning the dial wheel to bring the corresponding designating character thereon directly beneath the pointer 38. 75 80

On one face of the type wheel 34 there is a projecting ring which is slotted to form a plurality of equally spaced lateral projections 40, the number of such slots being the same as that of type bars 39 and having their 85 respective center lines in the same radial planes. The outer ends of these projections are beveled to receive in engagement therewith and between two adjacent ones thereof the correspondingly conformed lower end of 90 a spring actuated plunger 41, the purpose of which is to cause the proper centering of a selected type bar and to yieldingly hold the type wheel against rotation when not in engagement with the positive locking means, 95 which latter comprises a member 42 extending inwardly from the lower end of the side plate 31 and conformed to engage within the slot between two adjacent projections 40 when the type wheel is moved downward an 100 before the type characters are brought into engagement with the platen, thus holding the wheel positively against the slightest rotary movement during the printing operation. When the type wheel is turned to 105 bring a selected line of type into printing position, the plunger 41 is forced by the projections 40 upwardly against the action of a coiled spring 43 contained within a hollow screw 44 threaded into the cross bar 19 of 110 the yoke 18.

In the operation of machines of the character to which my invention pertains, the words or numerals are not only printed on the check but the paper is either perforated or the fibers thereof are broken throughout the printed surface and to accomplish this the type characters and platen have interengaging printing faces, such as pin points formed on the type which engage through 115 perforations therefor in the platen, or alternating parallel extending ridges and grooves formed on both members, the ridges of one member being adapted to enter the grooves of the other. This latter method is shown 120 as embodied in the machine herein shown and described, and it will thus be seen that in order to secure proper registration of the 125 irregular faces of type and platen the latter must necessarily be adjustably supported. 130

To this end, then, I provide the platen 14, made preferably of hard steel, and being in length and width substantially the same as the length and width, respectively, of the 5 type bars 39. The platen is seated in a slot 45 cut lengthwise of a support comprising the boss 15 formed on the centrally disposed transverse rib 3 of the base portion 1. The side walls thus formed on the boss 15 have a 10 slot 46 cut thereacross to receive the shoulder 47 of a screw 48 threaded longitudinally into the platen whereby upon a turning of the screw the same is caused to be the fixed and the platen the movable member. Vertical 15 adjustment is provided for by two screws 49 which are threaded upwardly through the support 15 and engage the bottom of the platen near its ends, while the platen is retained in proper position of adjustment by 20 a centrally disposed screw 50 threaded thereto into which extends upwardly through a slot opening therefor in the said support.

At 51 are seen two ink rollers extending parallel with the type wheel 34 and located 25 on opposite sides thereof below its axis. These rollers are supported in the outer ends of swinging brackets 52 pivotally connected at their inner ends to ears 53 bent from plates 54 secured to the members 55 which 30 comprise cover plates for the cut away lower portions of the front and rear walls of the head 8. The ink rollers are at all times held in yielding contact with the type wheel by the action of the coiled springs 56 encircling 35 the rods forming the pivotal connections between the brackets 52 and ears 53, and ink therefrom is supplied to the type when turning the wheel to bring different lines of type into printing position. A downward movement 40 of the type wheel causes the ink rollers to be swung farther apart and to permit this the cover plates 55 are of the curved formation shown. These plates are detachably held in place by having their bottom edges 45 curved to engage over rods 57 extending between the side walls of the head 8 and by a centrally positioned locking member for each such as that shown at 58 in Figs. 1, 2, 4 and 5. The rods 57 are preferably secured to 50 place, as seen in sectional detail in Fig. 14, by screws 59 threaded into the ends thereof through the side walls of the head 8.

At 13 are seen the usual knurled feed rollers which, in this machine, are located 55 one each side of and slightly in advance of the platen 14 with their peripheries engaging through slot openings therefor in the base plate 12 and projecting just above the top surface thereof. They are carried on 60 the ends of a sleeve 60 secured upon a rearwardly extending shaft 61 having bearings in the front wall and one of the ribs 2 of the machine base. This shaft is operable by hand, for which purpose a head 62 is pro-

vided at its outer end, and is held against 65 longitudinal movement by the inner end of a pin or screw 63 in the bearing 2 engaging the adjacent shoulders formed by the reduced portion 64 of the shaft, see Fig. 12.

Engaging the tops of the feed rollers 13 are small gripping rollers 65 mounted in 70 ears 66 extending outwardly from the lower portion of a plate 67 held in position against the outer face of the side cover plate 30 by screws 68. This plate 67 has a slight vertical movement in order to raise the rollers 65 from the feed rollers to permit the insertion of a check therebetween, such movement being provided for by the slots 69 through which the screws 68 extend, and the 75 means for raising the plate 67 comprises a lever 70 pivoted at its center to the side wall of the head 8. On the outer end of the lever 70 there is a projection 71 adapted to engage in a centrally disposed opening therefor in the plate 67, on the inner end there is formed a member 72 to be engaged by the finger of the operator, while the downwardly extending arm 73 has connected therewith one end of a coiled spring 74 the other end 80 of which is fastened to a pin in the side wall of the head 8. Operating the lever 70 causes a raising of the plate 67 which lifts the rollers 65 from engagement with the feed rollers 13, all of which is against the action 85 of the spring 74 which member causes the parts to resume their normal positions, being that indicated in the drawings, when pressure on the lever 70 is released.

The lower portion of the plate 67 is offset 100 toward the platen 14, see Figs. 5 and 6, for two reasons, first, that the gripping rollers 65 will engage the tops of the feed rollers 13 and, second, to form a gaging means, as shown in Fig. 18, whereby the check is advanced the proper distance after each printing operation to obtain equal spacing between the words or characters. This is illustrated in Fig. 18 wherein there is shown a check 75 on which has been printed the 110 word TWENTY and the check moved the proper distance, gaged by the member 67 by having the last letter "Y" just beyond the outer edge thereof, and in position for the succeeding word to be printed.

Within the top part 5 of the frame is a pinion 76 secured on the inner end of a shaft 77 revolvably mounted in a boss 78 formed on one of the supporting flanges 6 and having an operating head 79 on its outer 120 end. This pinion causes a movement forward and back of a check gage comprising a sheet metal rack 80 on the forward end of which is a cross head 81 having formed thereon a plurality of projections bent to 125 form inverted U-shape members 82 having their free ends engaging the surface of the base plate 12 and forming a gage or fence

against which the inner end of the check, see Figs. 2 and 13, engages and whereby a proper alignment of the printing is obtained.

The design of the machine is such that the space formed between the upright portion 5 of the top frame section and the depending head 8 permits instruments other than the ordinary check or draft, such as invoices, stock certificates, etc., indicated at 83 in Fig. 10 1, to be placed in the machine and printed on any desired line thereof.

It is necessary to provide means whereby, after each printing operation, the material printed on will be prevented from being raised from the plate 12 by the type in the return movement of the type wheel, and to this end I make use of a movable stripper such as shown in Figs. 5, 6, 10 and 11. The device is formed of thin metal and comprises a pair of arms 84 extending downward from a side arm 17 of the yoke 18 to the bottom of the type wheel 34 and thence under the wheel, as shown, such arms being spaced apart to allow a type bar 39 to engage 20 between them. Their free ends are connected by a cross piece 85 while their other ends are connected by a member 86 secured by screws to the bottom of the side arm 17 of the yoke with which they are raised and lowered. The portions of the stripper arms 84 under the type wheel are inclined slightly so that the free ends thereof will engage the check 75 just prior to contact therewith of the type, and consequently, on the upward 30 movement of the parts the resiliency of the arms in resuming their normal inclined position will cause them to hold the check in contact with the plate 12 for a brief period of time to effect a stripping of the check from the type while the latter moves clear of the platen. The arms 84, besides, performing the function of a stripper, by engaging under the lines of type adjacent the one in printing position guard against the check 40 coming in contact with such type, which otherwise might happen were the check not always perfectly flat upon the plate 12.

The operation of the machine is as follows:—

50 A check is placed on the supporting base plate 12 and the check gage properly adjusted to secure printing along the desired line. The lever 70 is then operated to raise the gripping rollers 65 allowing the check to be moved onto the feed rollers 13 after which by turning the shaft 61 the check is advanced the proper distance. A selected line of type is brought into printing position by turning the dial wheel 35 to bring the corresponding indication thereon under the pointer 38, and the lever 25 is pressed downwardly to cause the printing operation. The check is then advanced by turning the feed rollers 13, the proper distance being gaged, 65 if equal spacing is desired, by means of the

lower offset portion of the plate 67 in the manner stated, after which the next type selection is made and the lever 25 again operated to cause the printing of the succeeding word.

70

What I claim is:

1. In a check writing machine, a base, a platen, a support in the base for the platen, a cover plate on the base for supporting a check, and means for feeding the check; a casing member having vertically extending guide-ways formed therein, a yoke slideable in said ways, a type wheel secured to a shaft revolubly supported in said yoke, a dial wheel on said shaft, means for turning the type wheel to bring a selected line of type into printing position, ink rollers held in yielding engagement with said type wheel, means for yieldingly retaining the type wheel in its predetermined position, operating means for moving the yoke along said ways whereby the selected line of type and the platen are brought relatively toward each other to impress a check held between them, and means in the path of the type wheel in its downward movement for engaging and positively locking the same against rotation.

2. In a check writing machine, a base, a platen, a support in the base for the platen, a cover plate on the base for supporting a check, and means for feeding the check; a casing member having vertically extending guide-ways formed therein, a yoke slideable in said ways, a type wheel secured to a shaft 95 revolubly supported in said yoke, a dial wheel on said shaft, means for turning the type wheel to bring a selected line of type into printing position, ink rollers held in yielding engagement with said type wheel, means for yieldingly retaining the type wheel in its predetermined position, operating means for moving the yoke along said ways whereby the selected line of type and the platen are brought relatively toward each other to impress a check held between them, means in the path of the type wheel in its 100 downward movement for engaging and positively locking the same against rotation, and means carried by said yoke for stripping the check from the type as they move clear of the platen.

3. In a check writing machine, a base, a platen, a support in the base for the platen, a cover plate on the base for supporting a check, and means for feeding the check; a casing member having vertically extending guide-ways formed therein, a yoke slideable in said ways, a type wheel secured to a shaft 120 revolubly supported in said yoke, a dial wheel on said shaft, means for turning the type wheel to bring a selected line of type into printing position, ink rollers held in yielding engagement with said type wheel, means for yieldingly retaining the type 125 wheel in its predetermined position, operating means for moving the yoke along said ways whereby the selected line of type and the platen are brought relatively toward each other to impress a check held between them, means in the path of the type wheel in its downward movement for engaging and positively locking the same against rotation, and means carried by said yoke for stripping the check from the type as they move clear of the platen.

130

wheel in its predetermined position, an operating shaft mounted in said casing, connections between the said shaft and said yoke, means on the operating shaft for causing through the action of said connections a movement of said yoke whereby the selected line of type and the platen are brought relatively toward each other to impress a check held between them, elastic means for returning the parts to their normal position, means in the path of the type wheel in its downward movement for engaging and positively locking the same against rotation, and means carried by said yoke for stripping the check from the type as they move clear of the platen.

4. The combination, in a check writing machine, of a casing the side walls of which have vertically extending openings forming 20 guide-ways, a yoke slidable in said ways, cover plates for said openings for preventing lateral movement of the yoke, a type wheel revolvably supported in the yoke, an annular flange on one face of the type wheel 25 slotted radially to form a plurality of equally spaced projections, a fixed locking member carried by one of said cover plates and adapted to engage between two adjacent ones of said projections to positively hold 30 the type wheel against rotation, and means for reciprocating the yoke to bring said projections into and out of engagement with the said fixed locking member.

5. The combination, in a check writing machine, of a casing the side walls of which have vertically extending openings forming 35 guide-ways, a yoke slidable in said ways, cover plates for said openings for preventing lateral movement of the yoke, a type wheel revolvably supported in the yoke, an annular flange on one face of the type wheel 40 slotted radially to form a plurality of equally spaced projections the outer ends of which are beveled, means for yieldingly holding the 45 type wheel against rotation comprising a spring actuated plunger housed in the yoke and having one end conformed to engage between the beveled ends of two adjacent ones of said projections, a fixed locking member 50 carried by one of said cover plates and adapted to engage between two adjacent ones of said projections to positively hold the type wheel against rotation, and means for reciprocating the yoke to bring said 55 projections into and out of engagement with the said fixed locking member.

6. The combination, in a check writing machine, of a base, a platen, a support in the base for the platen, a cover plate on the 60 base for supporting a check, and check feeding means; a casing member supported above the base and having vertically extending openings in the side walls thereof, a yoke 65 slidably supported in said openings, side cover plates for said openings which pre-

vent a lateral movement of the yoke, side arms on said yoke and a type wheel secured to a shaft revolvably supported in said side arms, said wheel having a plurality of equally spaced lines of type characters on its periphery which extend parallel with the axis of rotation, a dial wheel on said shaft and means for rotating the shaft to bring a selected line of type into printing position, an operating shaft revolvably mounted in said casing, connections between such operating shaft and said yoke, means on the last named shaft for causing through the action of the connections a downward movement of the yoke whereby a check is impressed between 70 the platen and the selected line of type, an annular flange on one face of said type wheel which is slotted radially to form a plurality of equally spaced projections, a spring plunger in said yoke adapted to engage between two adjacent ones of said projections to cause a centering of the selected line of type and to yieldingly hold the type wheel 75 against rotation, a fixed locking member adapted to engage between two adjacent ones of said projections to positively hold the type wheel against rotation and with which said projections engage during the movement of the type wheel toward the platen, and elastic means for returning said 80 operating means and the parts actuated thereby to their normal position.

7. In a machine of the character described, a base, a platen, a fixed support in the base for the platen, a base cover plate 100 comprising a support for a check, a casing member, a supporting frame vertically movable in said casing and actuating means therefor, a wheel revolvably supported in said frame and having on its periphery a 105 plurality of lines of type characters, means for rotating said wheel to bring a selected line of type into printing position, and a spring arm carried by said frame and extending under the type wheel parallel with the selected line of type, said arm being 110 adapted to contact with the check before contact therewith of the type characters and, because of its resiliency in resuming its normal condition, to remain in contact with the 115 check to hold the same for a brief period against said cover plate to effect a stripping of the check from the printing faces of the type characters and platen as the same are moved relatively apart.

8. In a machine of the character described, a base, a platen, a fixed support in the base for the platen, a base cover plate comprising a support for a check, a casing member, a supporting frame vertically movable in said casing and actuating means therefor, a wheel revolvably supported in said frame and having on its periphery a 125 plurality of lines of type characters, means for rotating said wheel to bring a selected 130

line of type into printing position, and a pair of spring arms each secured at one end to said frame and connected to each other at their free ends, such arms extending downwardly to the bottom of the type wheel and bent at substantially right angles to extend under the wheel each side of the selected line of type and being adapted to contact with the check before contact therewith of 10 the type characters and, also, because of their resiliency in resuming their normal condition, to remain in contact with the check to hold the same for a brief period against said cover plate to effect a stripping 15 of the check from the printing faces of the type characters and platen as the same are moved relatively apart.

9. In a check writing machine, a base, a casing member supported above the base and 20 having side walls, two printing members movable relatively toward each other to impress a check held between them, one of such members being supported in the base and the other in the casing member; manually operable check feeding rollers revolu- 25 bly supported in the base, gripping rollers and means for holding them in yielding contact with the tops of the feeding rollers, and a gage plate slidably supported on one of 30 the said side walls and having arms carrying the gripping rollers.

10. In a check writing machine, a base, a casing member supported above the base and having side walls, two printing members movable relatively toward each other to impress a check held between them, one of such members being supported in the base and the other in the casing member; manually operable check feeding rollers revolu- 35 bly supported in the base, gripping rollers and means for holding them in yielding contact with the tops of the feeding rollers, and a plate slidably supported on one of the 40

said side walls and having arms carrying the gripping rollers, said plate having an 45 offset portion forming a gaging means, for the purpose specified.

11. In a check writing machine, a base, a casing member supported above the base and having side walls, a base cover plate comprising a support for the check, a platen and a support therefor in the base, a revolvably supported type wheel within said casing and movable to bring a selected line of type on the periphery thereof toward the platen to 50 impress a check held between them, check feeding rollers revolvably supported in the base and having their peripheries engaging through slot openings in said cover plate, gripping rollers and means for holding 55 them in yielding contact with the tops of said feeding rollers, a gage plate slidably supported against the outer face of one of said side walls and having arms carrying the gripping rollers, and operating means 60 for raising the said gage plate to permit the insertion of the check between the feeding and the gripping rollers.

12. In a check writing machine, a base, a platen and a support in the base for the 70 platen, a base cover plate comprising a support for a check, check feeding means, a casing comprising a rear portion extending upward from said base and a depending head supported from the rear portion, print- 75 ing mechanism coöperating with said platen supported in said head, a check gage comprising a cross-head having check engaging members formed thereon and a rack extending rearwardly from the cross-head, a pin- 80 ion engaging said rack and located within the rear portion of said casing, a shaft on which the pinion is secured, and means for operating the shaft.

HERMAN C. WELTER.
